UNITED STATES PATENT OFFICE.

DAVID S. KENNEDY, OF BROOKLYN, NEW YORK, ASSIGNOR TO MERGEN-
THALER LINOTYPE COMPANY, A CORPORATION OF NEW YORK.

LINOTYPE-MACHINE.

No. 817,646.

Specification of Letters Patent.

Patented April 10, 1906.

Application filed December 9, 1905. Serial No. 291,126.

To all whom it may concern.

Be it known that I, DAVID S. KENNEDY, of the borough of Brooklyn, county of Kings, and State of New York, have invented a new and useful Improvement in Linotype-Machines, of which the following is a specification.

My invention has reference to linotype-machines, wherein circulating matrices are composed or assembled temporarily in line, the composed line presented between two jaws or abutments which limit its final length, the line finally justified by expanding the double wedge spacers seated in the line, as shown, for example, in Letters Patent of the United States, No. 436,532. In these machines the composed line suspended in a vertically-movable carrier, known as the "first" elevator, is lowered by gravity to casting position between the two confining-jaws prior to justification.

It sometimes happens that the operator will compose the unjustified line to such length that it will not pass readily between the confining-jaws, and in such case there is a liability of the end matrices being displaced or thrown out of alinement by the frictional contact with the jaws. The aim of the present invention is to overcome this difficulty and to prevent the composed line of matrices from passing between the jaws in the event of its being of excessive length. To this end I arrange one of the confining-jaws and its operating mechanism in such manner that the jaw is advanced toward its companion previous to the presentation of the matrix-line, so that the distance between the jaws is for the time being less than the length of the justified line, so that the entrance of the line between the jaws is impossible. This fact makes it necessary for the operator to remove the superfluous matrices and in practice leads to his setting the line in the first instance of suitable length. The distance to which I move the jaw beyond its final position, although sufficient to prevent the entrance of the long line, is not such as to prevent the entrance of proper lines, which can be justified or expanded to the predetermined length.

My invention may be carried into effect by any suitable mechanism. The parts may be varied in form and arrangement to adapt them for use in the different linotype-machines now known in the art.

In the accompanying drawings I have shown my improvement embodied in a Mergenthaler linotype-machine, containing the jaw-adjusting mechanism of the character shown in the application of R. M. Bedell for Letters Patent of the United States, filed September 12, 1905, Serial No. 278,194, the mechanism shown differing from said application mainly in that it is adapted to carry the movable jaw inward or forward beyond its final operative point, whereas in the earlier mechanism its movements ceased at the final operative point.

Figure 1 is a perspective of the movable jaw and its actuating devices. Fig. 2 is a horizontal section on the line 2 2, Figs. 3 and 4. Fig. 3 is a face view of the two line-confining jaws, their actuating devices, and the first elevator with the matrix-line therein, the movable jaw being advanced to such position as to prevent the descent of the matrix-line. Fig. 4 is a similar view of the parts with the movable jaw in its final position at the completion of the justification of the line. Fig. 5 is a diagram illustrating the cam mechanism for actuating the jaw-adjusting devices.

Referring to the drawings, A represents a portion of the main frame, known as the "vise-frame," B and C, the two matrix-confining jaws; D, the matrices in the composed line; E, the expanding spacers or justifiers seated in the line; G, an adjustable rod seated against and supporting the horizontally-sliding jaw C; H, a block surrounding the rod G and adjustably connected thereto by a removable toothed pin I.

J is a vertically-movable slotted wedge encircling the rod G, seated on one side against the block H and on the opposite side against a bearing-plate K, which is in turn seated against a tubular supporting adjusting-screw L, threaded into the main frame loosely around the rod G. The wedge J is urged constantly upward by a spring k³, connecting it with the main frame, and is drawn downward at proper times by a lever p¹², the end of which works in a vertical slot k² in the lower end of the wedge. The upper end of the wedge is provided with two inclined or wedge faces k k', lying in reverse directions, so that whether forced upward or drawn downward to an extreme position it will act to advance the block H, its rod G, and the matrix-confining jaw C. So far as described

the parts are of the same construction as those in the application above referred to.

In carrying my invention into effect I combine with the lever p^{12} actuating devices which cause it to draw the wedge J downward until the jaw C is advanced so far that the distance between its face and the opposing face of jaw B is less than the length of the final or justified line, as shown in Fig. 3, so that the line of matrices supported in the vertically-movable second elevator M , if of proper length, is too long to descend between the jaws. Being arrested in its descent, the line cannot pass to the casting position, and the elevator M , in which the line is carried and by which the casting mechanism is tripped into action, is prevented from descending far enough to start said mechanism.

The wedge-actuating mechanism may be of any suitable character; but as shown in Fig. 5 it consists of a cam N , arranged to act on a roller on the upper side of the lever p^{12} for the purpose of depressing same against the stress of the spring k^3 . An adjusting-screw k^4 in the lower end of the wedge, upon which the lever acts, serves as a means of adjusting the throw of the wedge in advance of the jaw C with required accuracy.

In the operation of the machine the jaw C is set in its forward and abnormal position, as shown in Fig. 3, so that the descent of the matrix-line is prevented if it is of excessive length, but not otherwise. After the line is lowered to its position between the jaws, as shown in Fig. 4, the wedge rises and the jaw C retreats to such position that the distance between it and the jaw B is equal to that of the justified line. The spacers E are then driven upward to effect the preliminary justification or expansion of the line. The casting operation may now take place; but in order to secure more accurate alinement of the matrices it is usual to relieve the line from end pressure while they are being forced edgewise against the mold with the usual mechanism. For this purpose I prefer to make the cam, as shown, of such form that after the preliminary justification has taken place the wedge will rise to an intermediate position and relieve the block H , so that the jaw may retreat slightly. After the matrices are alined against the mold the wedge continues its upward motion to the position shown in Fig. 4, thereby setting the jaw C

again to the justifying position, in which it remains until after the casting operation is performed.

The essence of the present invention lies in positively advancing the jaw C beyond the justifying-point toward its companion and holding it so that the entrance of a long line between the jaws is prevented, and so long as this results the parts may be modified in form and arrangement.

Having described my invention, what I claim is—

1. In a linotype-machine, the combination of two matrix-confining jaws, means for presenting the composed line of matrices between said jaws, and an automatic mechanism arranged to positively approximate the jaws to a distance less than the length of the required line, and hold them in such position during the presentation of the matrices, whereby the admission of tight or overset lines between the jaws is prevented. 75

2. In a linotype-machine, the combination of two matrix-confining jaws, a composed line of matrices and spacers, means for seating the line between the jaws, means for closing the jaws to a distance less than the length of line demanded, and thereafter opening them to said length, and means for justifying the line after said separation. 80

3. In a linotype-machine, the combination of means for presenting composed lines of matrices and spacers, line-confining jaws, means for adjusting the spacers to justify the lines between the jaws, and means for setting the jaws: first, to a distance apart less than the required length of line, thereafter to a distance equal to the required length, and finally, to a greater distance apart to release the justified line. 90

4. In a linotype-machine, the two matrix-confining jaws, in combination with a wedge mechanism, acting to set the jaws, first, a distance apart less than the length or measure of the required line, and second, a distance apart equal to the length of the line. 95

In testimony whereof I hereunto set my hand this 4th day of December, 1905, in the presence of two attesting witnesses.

DAVID S. KENNEDY.
